[57] ABSTRACT

Data processing apparatus arranged to perform a method for the search, simultaneously in several networks, for a set of optimum component trajectories respecting constraints of inter-dependence of these networks, these trajectories connecting in each network a starting point node and a target point node ; this method is carried out by performing a series of retrograde investigations from a final situation to an initial situation and thus determining step by step the desired set of optimum component trajectories ; the apparatus may include : centers for simulating each network, centers of association of nodes or links of different networks for simulating the inter-dependence constraints of the networks, posting members for target and starting points nodes, a center of coordination for coordinating the transmission of signals to a number of lines which connect said different centers with the aid of temporary memories.

DATA PROCESSING APPARATUS

This invention relates to data processing apparatus for the analysis of networks representing various possibilities of passing from certain states of one or several systems to other states, in the search for the existence of an optimum passage between two states, one initial the other final. The inventor's earlier U.S. Pat. No. 3,558,868 of Jan. 26, 1971 discloses a method and device suitable for solving this type of problem in the case of a single network composed of a set of nodes connected by orientated links. If in this network the nodes correspond to points all representative, in a suitable geometric space, of states of a system and if the meshes or links correspond, with weightings which may possibly be different, to all the possible elementary trajectories around the various nodes, this method consists of: identifying a group of nodes, this method consists of: identifying a group of nodes representing a first population of points, called starting points, and another group of nodes representing a second population of points, called arrival points; emitting simultaneously, from all the nodes constituting the population of arrival, signals progressing step by step along the meshes or links of the network towards the intermediate nodes; normally preventing the reception of more than one of these step by step signals by these intermediate nodes; determining the starting node which is the first reached by one of these signals and then interrupting the progression of these; and finally setting up from this starting node determined in this way a connection terminating at the arrival node from which has started by signal which has been the first to reach the determined starting node.

This method accordingly permits the determination of the coupling from starting point to arrival point, corresponding to the optimum trajectory in the network considered, i.e. a trajectory including the minimum number of steps, using the convention that the number of steps necessary to move through a link is fixed by its weighting. In certain applications there is only one single starting point and one single arrival point.

Although the number of factors capable of intervening in the definition of the states of the system considered may be very high, the representative network being then defined in a geometrical space comprising a great number of dimensions, this method is not applicable to problems which are concerned with the utilization of several networks which have to be made interdependent for representing the possible or conceivable developments of several systems reacting on one another. In this type of problem the solution is represented by the existence of an optimum passage between an initial complex situation defined by the identification in each of the networks of a node called a starting point, and a final complex situation, defined by the identification in each of the networks of a node called target point; this passage should take into account not only internal constraints of each network, but also constraints between these networks.

The path between an initial complex situation and a final complex situation is carried out in a succession of steps called a transformation. Each step comprises, in at least one of the networks, the passage from a node to an adjacent node. The ensemble of the nodes reached at the end of a step constitutes an intermediate situa-

tion. The weighting of the order p of a mesh is equivalent to a sequence of p unit meshes or links.

Given a transformation, the passage from an intermediate situation to another cannot in general be carried out by passage from a node to the following, in each of the networks simultaneously, by reason of the inter-dependence constraints among the networks. The existence of these inter-dependence constraints is expressed in effect by the associations of meshes (links) or nodes which incorporate for the transformation the obligation (or prohibition) of certain intermediate situations, or of the simultaneous passing through certain meshes or links belonging to different networks.

Thus, one can encounter associates of nodes and associations of links; these latter may themselves be divided for example into associations of links as a function of direction and associations of links as a function of their weight.

If the optimum passage between the initial situation and the final situation is defined as the transformation which includes the minimum number of steps, by reason of the constraints this optimum passage is not in general the combination of all the optimum trajectories determined independently in each network. This excludes therefore the repeated application of the above known method to each network. By way of example the problem set out above is met with in problems of the planning of tasks to be performed with a finite number of means, such as the organization of railway networks, telephone networks, and so on.

For solving this type of problem, the plain generalization of the method defined above for its use in several networks with simultaneous progression of signals in these networks is impracticable. If each network is defined in a sub-space (the number of dimensions having little importance), each of the networks may be considered as the projections in each of the sub-spaces of an imaginary network which would exist in a sub-space, which imaginary network represents the inter-dependence of these networks and in which the initial situation and the final situation would each be represented by a node.

An optimum trajectory in this imaginary network between the initial complex situation and the final complex situation may project itself in a particular sub-space in the form of a trajectory including one or several loops. Such a trajectory is obviously not optimum between the starting point and the target point of the network considered, but it will be called optimum component trajectory in this network. It will be necessary to review the trace to describe the optimum trajectory composed by the set of optimum component trajectories of the real networks in the course of the search.

In the method of searching for the optimum trajectory in a single network, the possibility of extracting looped trajectories is eliminated by inhibiting the reception of more than one signal by an intermediate node in the course of the retrograde search represented by the progression of step by step signals between the arrival points and the starting points.

The necessity for admitting possible looped optimum component trajectories in the networks accordingly prevents the use of this method in the case of several inter-dependent networks and the reception of more than one signal by a node must be accepted.

If one carries out a retrograde search in each of the networks between the target point and the starting point, it is not possible to stop the retrograde progression when the starting point is reached in one of the networks only; it is necessary to wait until it is reached in all the networks simultaneously. At the moment when this search is stopped, it is then impossible to determine as previously in each network an immediate connection between the starting point and the arrival point: nothing enables distinction to be made between the optimum component trajectory and the other trajectories.

The aim of the present invention is to provide means by which a determination may be made of the optimum component trajectories in several inter-dependent networks between the starting points in these networks, the set of which constitutes an initial situation, and the target points, the set of which constitutes a final situation, overcoming the difficulty which has just been mentioned.

The present invention consists in data processing apparatus arranged to perform a method for the search for a set of optimum component trajectories in a set of networks, which includes the steps of starting a retrograde step from each of the target points of the networks and, when all the starting points have been reached simultaneously by the search, there is identified and stored for each network, as belonging to the optimum component trajectory sought, the last node reached by the retrograde search before the starting point, said last node then being used as a fresh starting point for a further retrograde search from the same target point.

The invention further consists in data processing apparatus arranged to perform a method for the search, simultaneously in several networks, for a set of optimum component trajectories respecting constraints of inter-dependence of these networks, these trajectories connecting in each network a starting point node and a target point node, in which method:

- a set of starting point nodes characterizes an initial complex situation A;
- a set of target point nodes characterizes a final complex situation Z;
- the transition between the initial complex situation A and the final complex situation Z is carried out in a succession of steps constituting a transformation; each step comprises the passage from one node to an adjacent node in at least one of the networks;
- the set of nodes reached at the end of a step constitutes an intermediate complex situation;
- the optimum component trajectory of each network is defined as that trajectory which permits the transformation in the minimum number of steps; and at least one of the networks has several optimum component trajectories, called equivalent, in the case where there is more than one such transformation;

wherein the method is carried out by performing a series of retrograde investigations from the final situation Z towards the initial situation A in the following way:

- i. starting from the target point z of the final situation Z, determining in each network predecessor nodes y which constitute intermediate situations Y_i from which the final situation Z is accessible in one step,

- this determination representing the first step of a retrograde investigation;
- ii. then, starting from the nodes y constituting these intermediate situations Y_i , determining, still in each network, the predecessor nodes x constituting intermediate situations X_i from which the intermediate situations Y_i are accessible in one step, this determination representing the second step of the retrograde investigation;
- iii. continuing thus step by step with the retrograde investigation up to a step of order n which terminates in a number of intermediate situations B_k among which there is an intermediate situation B_o accessible in one step from the initial situation A;
- iv. registering the successor nodes b constituting the intermediate situation B_o as being each the end of a first elementary activity of the optimum component trajectory sought in each network;
- v. proceeding to a further retrograde investigation from the final situation Z, taking as a new initial situation the situation B_o , for determining a situation C_o accessible in one step from the situation B_o and consisting of successor nodes c each of which is the end of a second elementary activity of the optimum component trajectory sought in each network; and
- vi. carrying out further retrograde investigations step by step until the desired set of optimum component trajectories has been determined.

The method referred to above also applies to the case where there is in each network a population of starting points and a population of target points. An important feature of the method is the simultaneous nature of the retrograde investigation from each target point in all the networks. This investigation progresses in each network taking into account the inter-dependence constraints. As soon as there is reached simultaneously a set of nodes comprising a starting point in each network, the retrograde investigation is stopped and a step of the transformation is carried out from these starting points. This step defines in each network a fresh starting point for the following retrograde investigation which then develops in each network from all the target points and finishes at this single fresh starting point. In this way there is built up the optimum component trajectory which connects in each network the previously selected starting point with the first target point encountered.

The apparatus is arranged to process data relating to the various networks with their nodes and links, whether weighted or not, and data relating to the various associations defining the inter-dependence constraints of the networks.

Each network may be taken into account in the machine by means of a connection center, comprising as many node elements as there are nodes in the network, and by means of a recording center comprising as many link elements as there are links among the various nodes of this network. There will accordingly be as many connection center/recording center couples in the machine as there are networks to be taken into account.

The constraints may be taken into account in association centers comprising elements connected to the elements of the connection or recording centers of the

various networks which their task is to join. For instance, an element of association of three nodes belonging to different networks will be connected to each of the corresponding node elements by a line called line of interrogation and a line called line of authorization. This element is constituted by a logical gate which in reply to a signal on one of its interrogation lines will transmit a signal on the corresponding authorization line only if a certain condition, of interest to the other two nodes, is satisfied; this condition may for instance be the presence or absence of simultaneous interrogations coming from these other elements; the existence of the signal of authorization may also be subordinated to the existence of another condition such as the previous memorization of the element, an information signal coming from adjacent elements, or the result of some other logical operation connected with this element.

The invention still further consists in data processing apparatus for carrying out a method for the simultaneous search in several networks for certain trajectories, called optimum component trajectories, respecting inter-dependence constraints of these networks, these trajectories connecting in each network a starting point node and a target point node, wherein the apparatus includes :

A. for simulating each network :

- i. a connection center comprising as many elements called node elements as there are nodes in the network;
- ii. a recording center comprising as many elements, called link elements, as there are links in the network;
- iii. lines called OACI which connect each node element to all the link elements starting from this node;
- iv. lines called EACI which connect each node element to all the link elements of which this node is the end;
- v. these lines are adapted to assume functions of interrogation (INT) if they carry signals issued from node elements towards link elements, or functions of authorization (AUT) if they carry towards the node elements signals issued by a link element on which there has been coincidence of signals INT OACI and INT EACI; and
- vi. lines called SORT ACT ensuring the outlet of information relating to the elementary activity accomplished in each network at each step;

B. for simulating the inter-dependence constraints of the networks:

centers of association comprising elements of association of node elements of different networks and/or of link elements of different networks to which elements they are connected by lines, called lines of interrogation if they carry signals to a center of association and called lines of authorization if they carry signals coming from a center of association;

C. posting members for a target point node and a starting point node for each network;

D. a center of co-ordination of the step by step execution of various phases of the search, simultaneously in the centers materializing each network, this search comprising alternate phases β and γ

succeeding each other until the node posted as target point is reached and in which :

- i. the first step of a retrograde investigation phase starts by the transmission, from each node element posted as target point, a signal to the line INT EACI which departs from there and the systematic transmission of signals to all the lines INT OACI, the node elements which receive in return a signal of AUT OACI, after verification in the centers of association corresponding to possible predecessor nodes of the target points;
- ii. the second step of the phase β develops in an identical manner from predecessor node elements as do the following steps;
- iii. a logical AND gate β for detecting the step at the end of which the node elements posted as starting points in each network receives simultaneously a signal AUT OACI and then controlling the stopping of the phase β ; and
- iv. the phase γ starts after the stopping of the phase β by the sending of a signal to the line INT OACI issued from the starting node element in each network, and by the sending of a signal to the lines INT EACI of the node elements reached during the last step of the retrograde investigation phase β to terminate in the identification for each network, as the fresh starting node, of a successor node receiving the signal AUT EACI, the elimination of the identification as the starting node of the preceding element, and the issue of a line SORT ACT in each network of information relative to the activity thus accomplished, and

E. temporary memories B2 associated with the nodes for identifying the predecessors constituting intermediate situations reached at the end of step β and connected to the posting members of the target point nodes; memories B₀ associated with starting point nodes for identifying the successors constituting the actual or present situation and connected to posting members of the starting point nodes; and buffer memories B1.

Preferably, the recording center comprises for each node element a link element of zero value as well as other arrangements which will be examined below.

The apparatus defined above will hereinafter be described in greater detail by way of example with reference to the output of a combinatory active memory comprising matrix structures with at least two inputs and temporary memories of known construction enabling the representation of the developments of a system defined by several parameters capable in each case of taking a finite number of values, called situations, and of undergoing an equally finite number of variations, called actions, from each of these situations.

The various possible states of the determined system are defined for each parameter by a plurality of situations; from each situation the parameter may undergo one or several variations or actions; these actions translate the possibility for the system of passing from a situation to another in accordance with this parameter. The various possible situations of the system and the various actions among the situations may accordingly be represented by a network comprising nodes/situations and links/actions. Moreover, the networks as

sociated with the various parameters are inter-dependent since the transition of this system from one state to another is translated in general by the passage from a situation to another in accordance with changes in several parameters simultaneously.

A given evolution of the system is constituted by the passage from an initial complex situation, defined by the set of the values of the parameters at an initial instant to a final complex situation defined by the set of the final values of the parameters; this is accordingly a transformation.

If the transformations of a given system are recorded in an active memory in such a manner that the possible situations and actions of this system in accordance with each parameter are represented by a network, there may be applied to this active memory a method and a device for extraction of the type previously defined for the search of optimum component trajectories in several inter-dependent networks. Of course, at the same time as the situations and the actions, there will be recorded the associations which constitute the inter-dependence of the parameters.

The amplitude of a transformation is defined by the number of complex actions or number of steps necessary for connecting these two situations.

The optimum transformation will then be that which comprises the minimum number of steps.

A transformation of a system defined by n parameters may conveniently be represented in an associated n -dimensional space. In this space, a complex situation will be represented by a point and a complex action by a vector; a transformation will accordingly be represented by the connection of two points representative of complex situations by a chain of vectors representing the chain of complex actions.

The active memory which will now be described has two functions:

a function of storage of information relating to complex transformations in accordance with a process called "recording process." Thus, the apparatus will be able to store a great number of complex transformations connecting in pairs initial situations to final situations. It will also be able to store a set of complex situations and to be endowed with certain possibilities of actions in this set, this case being able to be a limit case of the first form of storage;

a function of "extraction" which, from stored information, permits the supply of information on the realization of complex transformations. In particular, it permits the determination to be made of how one can join two complex situations which had never previously been in the experience of the apparatus, by determining the transformation comprising the minimum number of steps necessary for this purpose.

It will be seen that the active memory, with its characteristic memory portion and its characteristic extraction system, permits the solution of complex problems such as the determination of strategies, (i.e. sequences of successive decisions to be taken in the accomplishment of any task. Each stage of a strategy is accompanied by a fan of possible routes thus requiring a decision; the number of stages increasing and the possibilities of choice at each level multiplying. The total number of possible strategies, of which it is not known in advance whether each will be good or bad, thus in-

creases in considerable proportions. At the present moment the problem, which is posed in a most crucial way in numerous activities, is to select a strategy which will at least be good and will if possible be the best.

Traditional calculating and data processing machines approach this problem by examining successively all the possible combinations capable of constituting a solution. This is obtained only at the expense of a considerable increase in the size of the memories of the machines and, as time progresses, machines quickly become of a considerable size, even prohibitive. Moreover, such systems are unsuited for the unforeseen introduction of fresh information during the course of processing and this is particularly so for real time operation.

The active memory described above, by virtue of the principles on which it is based, enables these problems of strategy to be approached more easily than with the traditional systems. The active memory works in a synthetic, experimental, evolutive and parallel manner, in contrast to most traditional systems which work in an analytical, numerical, set and sequential manner.

The active memory is synthetic to the extent that by the storage in a single memory element or in a small number of memory elements, it permits the association of a number of values, which number may be considerable, such as for instance, the co-ordinates of a point in an n -dimensional space.

It stores an "experimental behavior." It possesses in fact memory elements the storage state of which brings about the transition from one value of a parameter to another. Accordingly, it enables the registration to be made of the transition of a particular set of parameter values to at least one other particular set of values of these parameters characteristic of a resultant state of a system.

The memory is active in the sense that the writing of a new behavior may be carried out in the memory itself from the actual state of storage, and in that the interrogation of this memory, or extraction, is carried out also in the interior of this memory, taking into account its actual state of storage, which is capable of being modified in the course of extraction.

The active memory is synoptic, i.e. it works in parallel by simultaneous interrogation in all the possible circuits to take into account stored information.

The remainder of the specification is identical to that portion of the specification of U.S. Application Ser. No. 858,027, now U.S. Pat. No. 3,651,495, starting at column 5, line 52, sub-heading "Terminology."

What we claim is:

1. Apparatus for the extraction of information for use with data processing apparatus which includes matrices having bistable elements, and temporary memories; a coordination center (CC) controlling the bistable matrices and the temporary memories, said apparatus analyzing an external system defined by a plurality of parameters, each capable of taking a finite number of values and to undergo, starting from each said values, a finite number of variations, the data processing machine comprising

1. a plurality of basic, functionally non-subdivisible sub-assemblies including
(a) as many connection centers (FIG. 3: CL; CLX, CLY . . .) as there are parameters to be

memorized, each connection center (CL) comprising as many connection elements (FIG. 8: EL) as there are possible values for the parameter to be considered, each connection element (EL) comprising a first separate bistable memorization element (BO 1108);

b. as many bi-dimensional recording center matrices (FIG. 3: CI; CIX, CIY . . .) as there are parameters, each recording center comprising recording elements (FIG. 9: EI) included in the recording center matrices, each recording element comprising a separate second bistable memorization element (B 1201), each state of said second bistable memorization element corresponding to one of the possible variations of one of the values of the parameter of the respective matrix, a first AND gate (1203), the output from the second bistable memorization element (B 1201) forming one input to said first AND gate (1203);

c. at least one value-associative matrix (FIG. 3: CAS; CAS XY . . .) comprising as many association elements (FIG. 7: EAS) as the number of possible associations, and having third bistable memorization elements (FIG. 7: B 1004), capable of having two values, each one corresponding to a different parameter, and fourth and fifth bistable memorization elements (B1 1007; B2 1012), and a second AND gate (1011), said fourth and fifth bistable elements being connected to said second AND gate (1011);

II. extraction apparatus, comprising

a. a first group of four types of interconnecting lines, interconnecting the connecting elements (FIG. 8: EL) with respect to a parameter, to the recording elements (FIG. 9: EI) with respect to the same said parameter, said four types of lines including:

1. a first type of said lines (FIGS. 8 and then 9: INT OACI) interconnecting the output from a first OR GATE (1110) of a connecting element (EL) to the first input of said first AND gate (1203) of a row of recording elements (EI) associated with one of said values;

2. second types of lines (FIGS. 9 and then 8: AUT OACI) interconnecting the output of a second OR gate (1206) from a recording element (EI) to the first input of a third AND gate (1111) of a corresponding connecting element (EL), the output of which is connected to an input of a fourth AND gate (1113);

3. third types of lines (FIGS. 8 and then 9: INT EACI) interconnecting the output of a third OR gate (1103) of a connecting element (EL) and corresponding to a particular value of a parameter, to the second inputs of said first AND gates (1203) of the recording elements (EI) so that the variation of a value of the parameter corresponding to the columns in which each recording element (EI) is arranged defines the same extreme value for the array of recording elements (EI) connected to the same line of said third type (INT EACI)

and said extreme value is that of said connecting element (EL), the input of said third OR gate (1103) being connected to the outputs of fifth and sixth AND gates (1102, 1104);

4. fourth types of lines (FIGS. 9 and then 8: AUT EACI) interconnecting the outputs of fourth OR gates (1208) of the recording elements (EI) to a first input of a seventh AND gate (1112) of a corresponding connecting element (EL);

b. recording lines (SORT ACT) interconnecting eight AND gates (1207) of the recording elements (FIG. 9: EI) such that each of said recording lines (FIG. 11: SORT ACT) corresponds, for the same column of a recording matrix, to the same variation controlling the actual value of the parameter;

c. the extraction apparatus further including said value-associative elements (FIGS. 3 and 7: EAS) and a second group of three types of interconnecting lines, interconnecting the connecting elements (FIG. 8: EL), each, with respect to a value of a parameter to at least a row of value-associative elements (EAS) with respect to the same value of a parameter including;

1. fifth types of lines (FIG. 8, then 7: INT CAS; INT CAS X, INT CAS Y) interconnecting the outputs of a buffer OR gate (1113) of a connecting element (EL) to at least one of two inputs (INT CAS X, INT CAS Y, . . .) of ninth AND gates (FIG. 7: 1006) of a row of associative elements (EAS), a group of associative elements forming an association center (CAS), the center of association (CAS) formed by said group of elements being associated with a predetermined value with respect to said parameter, the outputs of said ninth AND gates (1006) being connected to one input of said fourth bistable elements (1007), and to the input of an inverter (I 1022);

2. at least two sixth types of lines (RET B1) for each center of association (CAS) associated with a predetermined value (CAS; RET B1X, RET B1Y . . .), having at least two fifth and sixth OR gates (1016, 1017), each associated with at least two rows of at least one center of association (CAS) associated with said predetermined value, for each parameter, each row of elements (FIG. 7: EAS) being connected to an input of the ninth AND gate (1106) of the connecting element (FIG. 8: EL) corresponding to the value of the parameter defined by said row;

3. at least two seventh types of lines (RET B2) for each center of association of the same predetermined value (FIG. 7: CAS; RET B2X, RET B2Y . . .) having at least two seventh and eighth OR gates (1019, 1020), each associated with at least two rows of at least one center of association (CAS) of said predetermined value, for each parameter, each row of elements (FIG. 7: EAS) being connected to an input of a tenth AND gate (1101) of the connecting element (FIG. 8:

- EL) corresponding to the value of the parameter defined by said row;
- d. as many display lines (FIG. 8: MEM B2) of the values for the group of parameters corresponding to the final state of the system to be controlled, as are possible values for each parameter, each said lines being connected to an input of the buffer OR gate (1113) of a connecting element (EL) which corresponds to the same value of the same parameter;
- e. as many display lines (FIG. 8: MEM B0) of the values for the group of parameters corresponding to the initial state of the system to be controlled as are possible values for each parameter, each said line (MEM B0) being connected to an input of a ninth OR gate (1118) of the connecting element (EL) which corresponds to the same value of the same parameter;
- f. the coordination center (CC) executing, step by step, the different phases of search, comprising:
1. lines γ connected to a second input of fourth AND gates (1109) and said sixth AND gates (1104) of the connecting elements (FIG. 8: EL);
  2. start lines (A) connected to the inputs of tenth OR gates (1120) of all the connecting elements (FIG. 8: EL);
  3. control lines (RAZ B1) connected to all eleventh AND gates (1023) of the value association elements (FIG. 7: EAS);
  4. an eighth line (FIG. 11b: AUT SORT ACT) connected to all the first inputs of twelfth AND gates (1408), the other second inputs of which being connected to all of said recording lines (FIG. 9: SORT ACT) of the same column of recording elements (EI) in a recording matrix (CI);
  5. ninth lines (BT2) connected to:
- one input of said fifth AND gates (1102), said third AND gates (1111) and a pair of thirteenth AND gates (1112, 1119) of all the connecting elements (FIG. 8: EL), and
- one input of fourteenth AND gates (1009) of all the association of value elements (FIG. 7: EAS);
6. tenth lines (BT1) connected to one input of all the second AND gates (1011) of all the association of value elements (FIG. 7: EAS);
7. further control lines (RAZ B2) connected to one input of the fifth bistable memory element (B2 1012) of all the association of value elements (FIG. 7: EAS);
8. eleventh lines (FIG. 7: FIN β CAS) connected to the output of an eleventh OR gate (1021), one each being associated with a center of value association (FIG. 7: CAS) and connected, in turn, to the inputs of fifteenth AND gates (FIG. 11a: 1330);
9. twelfth lines (FIG. 8: INF B0), and a comparator (FIG. 11a SAFI) and a sixteenth AND gate (FIN EXT), the twelfth lines being connected to the input of the comparator, the output thereof being connected to said sixteenth AND gate (FIN EXT) and interrupting the extraction step; and

10. a clock means, said clock providing timing signals (FIG. 15), one of said timing signals providing a signal (FIN β) to the output of said fifteenth AND gate (FIG. 11a: 1330) and then, providing further timing signals (FIG. 16), to be followed by said first timing signals (FIG. 15) until the signal is derived from said sixteenth AND gate (FIG. 11a: FIN EXT), said signal from said sixteenth AND gate stopping the further generation of clock signals.
2. Apparatus according to claim 1, wherein:
- I. said machine comprises a fourth sub-assembly, said fourth sub-assembly including at least one matrix (FIG. 3: CAA; CAA XY) formed of elements of variable association of values (FIG. 10: EAA), said elements of variable association of values including six bistable memorization elements (FIG. 10: B 1301), each corresponding to an association of at least two variations of value, each associated with a different parameter; and wherein the extraction apparatus further comprises
- II. a thirteenth type line (INT CAA) interconnecting the output of a twelfth OR gate (FIG. 9: 1204) with all the recording elements (EI) of a column to one of the inputs of a seventeenth AND gate (1304) of all the elements of variable association of value (FIG. 10: EAA) of a row, of at least one of the matrices (CAA; lines INT CAA X, INT CAA Y, FIG. 10); and
- fourteenth type lines (FIG. 10: AUT CAA; AUT CAAX, AUT CAAY), connected to the outputs of thirteenth and fourteenth OR gates (1305, 1306), all said fourteenth type lines (AUT CAA) of one row of a center of association (CAA) being connected to an input of an eighteenth AND gate (FIG. 9) of all the recording elements (EI) of a column of the recording matrix (CI), the other input of said eighteenth AND gates (1205) being interconnected to the output of said first AND gate (1203), the output of said first AND gate being connected to one input of said second OR gate (1206).
3. Apparatus according to claim 1, wherein each of the elements of association (FIG. 7: EAS) comprises a fifteenth OR gate (1008) connected to the output of said fifth bistable memory elements (B2 1012) of at least some of the elements of association (EAS) accessible during a single variation of value of the parameters associated with said element;
- the output from said fifteenth OR gate (1008) being connected across said fourteenth AND gate (1009) to one input of the ninth AND gate (1006).
4. Apparatus according to claim 1, wherein each of the sixth type lines (RET B1) with respect to the same parameter are connected to the inputs of nineteenth AND gates (1106), to form a line of the connecting elements (EL; FIG. 8) of the parameter;
- and wherein the seventh type lines (RET B2) with respect to the same parameter form the inputs to the tenth AND gates (1101) of a line of the connecting elements (EL) of said parameter;
- the output from said tenth AND gates (1101) being connected to the other input of sixteenth OR gates

(1102) and to the inputs of said sixth AND gates (1104); and wherein the fourteenth type lines (FIG. 10: AUT CAAAX, AUT CAAAY) are provided, relative to the same parameter, and forming one of the inputs to a twentieth AND gate (FIG. 11: 1401).

5. Apparatus according to claim 1, wherein the tenth OR gate (1120) of each connecting element (FIG. 8: EL) is excited by the signal from the start line (A) at a clock time (βT_2); and the thirteenth AND gate (1119) is validated by the ninth line (BT2), connected to one of the inputs of said thirteenth AND gate (1119), the output being connected to one of the inputs of the first OR gate (1110), energizing the first type line (INT OACI).

6. Apparatus according to claim 1, wherein the start line (A) connects the start signal to a twentieth OR gate (FIG. 11b: 1403), the output from said twentieth OR gate (1403) being connected to validate a twenty-first AND gate (1402), the output from said twenty-first AND gate (1402) forming the connection to the line, or column of said thirteenth lines (INT CAA).

7. Apparatus according to claim 1, wherein each of the elements of association (EAS) comprises one of said fourth bistable memorization elements (B1 1007), said bistable elements having a control and reset input, the reset input being connected to said control line (RAZ B1) over said eleventh AND gate (1023), the other input of said eleventh AND gate (1023) being connected to the output of an inverter (I 1022).

8. Apparatus according to claim 1, wherein each element of association (FIG. 7: EAS) comprises a seventeenth OR gate (1010), the inputs of said seventeenth OR gate (1010) being connected to an output (1013) of said fifth bistable memorization element (B2 1012), the output of the fourteenth AND gate (1009) and a general control line ($\bar{P}$), said general control line suppressing the constraint of a validation by the ninth AND gate (1016) or from the output of the fourteenth AND gate (1009) or from the output of the fifth bistable memorization element (B2 1012).

9. Apparatus according to claim 1, wherein each element of association (FIG. 7: EAS) of a column of each association of values matrix (FIG. 3: CAS) comprises a fifteenth line (BOX) forming an input line, said input line (BOX) being common to all elements in a column, and being connected to a twenty-second AND gate (1018) and a sixteenth input line (BOY) common to all the elements in a row being connected to a second input of said twenty-second AND gate (1018);

45 the third input to said twenty-second AND gate being formed by the output from the fourth bistable memorization element (B1 1007), the output from said twenty-second AND gate (1018) forming one of the inputs to the eleventh OR gate (1021), the other inputs of said eleventh OR gate 50 1021 being formed by the outputs from all the twenty-second AND gates of the respective matrix.

10. Apparatus according to claim 1, wherein fifteenth OR gates (1008) are provided, the inputs to said fifteenth OR gates (1008) being formed by the outputs of the fifth bistable memorization elements (FIG. 7: B1 65 1012) of the elements of association (EAS) adjacent the respective elements.

11. Apparatus according to claim 1, wherein the fourth AND gate (1109) has as a second input the output of the first bistable memorization element (BO 1108), the output from said fourth AND gate (1109) being connected to the second input of the first OR gate (1110).

12. Apparatus according to claim 1, wherein a reset line (RAZ B0) is provided, said reset line (FIG. 8: RAZ B0) being common to the apparatus and forming a second input to the first bistable memorization element (BO 1108).

13. Apparatus according to claim 4, wherein each connecting element (FIG. 8: EL) includes a twenty-third AND gate (1107), a first input of said twenty-third AND gate (1107) being connected to the output of the nineteenth AND gate (1106);

15 and a seventeenth overall authorization line (AUT 1) is provided, forming a second input to said twenty-third AND gate (1107), the output from said twenty-third AND gate (1107) forming a second input to the ninth OR gate (1118).

14. Apparatus according to claim 2, wherein each recording element (FIG. 9: EI) includes the eighteenth AND gate (1205), the output of said eighteenth AND gate (1205) forming the inputs to the fourth OR gate (1208) and a seventeenth OR gate (1207).

15. Apparatus according to claim 14, wherein each recording element (FIG. 9: EI) includes said seventeenth OR gate (1207), an additional input thereof being connected to the recording line (SORT ACT) of the column of the matrix of recording elements in which the recording element (EI) is located.

16. Apparatus according to claim 1, wherein each recording element (FIG. 9: EI) has the second input of the fourth OR gate (1208) connected to the output of the fourth type lines (AUT EACI) of the recording elements.

17. Apparatus according to claim 1, wherein each recording element (FIG. 9) comprises an eighteenth line (GEN), to the group of recording elements of one matrix, said common line (GEN) forming an input to an eighteenth OR gate (1202), the output of which forms one of three inputs to the first AND gate (1203).

18. Apparatus according to claim 1, comprising elements of association of variation of values (FIG. 10: EAA), said elements comprising, each, an eighteenth OR gate (1303), having one input formed by the output of the sixth bistable memorization element (B 1301), and a second input formed by an eighteenth line (PROJ) common to all the elements of the matrix, the output from said twentieth OR gates forming a third input to a seventeenth AND gate (1304).

19. Apparatus according to claim 1, wherein, in each element of the variation of association of values (FIG. 10: EAA),

40 a nineteenth reset line (RAZ CAA) is provided, common to the apparatus, said nineteenth reset line forming a second input to a sixth bistable memorization element (B 1301).

20. Apparatus according to claim 1, wherein each recording line (SORT ACT) has a twelfth AND gate (FIG. 11b: 1408) inserted therein which is energized by the eighth type line (FIG. 11a, then FIG. 11b; AUT SORT ACT), the recording lines (SORT ACT) of one recording matrix (CI) being all connected to a multiple

input gate (FIG. 11a: PAM 2301), said multiple input gate (PAM 2301) energizing either a twentieth line (SAM) or, if more than one line is to be energized, the recording lines (SORT ACT) of each recording matrix, or a twenty-first line (O) if no single one of the recording lines (SORT ACT) is energized, the twentieth output lines (SAM) from all the gates (PAM 2301) providing to the coordination center (CC) the information from the twenty-first line (O) over a nineteenth OR gate (2401), the other inputs of which being connected to the ZERO outputs of all the multiple gates (PAM),

the output from said multiple gates (PAM 2301) further delivering to the coordination center (CC) data of information > 1 over a twenty-first OR gate (2402), the other inputs of which being connected to the inputs > 1 of all the other multiple gates (PAM 2301), the output from said twentieth OR gate (2402) being connected to a twenty-fourth AND gate (2405), the other input of which is connected to a twenty-eighth AND gate (PACN) over an inverter (2406).

21. Apparatus according to claim 1, wherein an inter-parameter hierarchy circuit between the recording matrices is provided (FIG. 23), comprising:

a seventh bistable memorization element (BAM 2304) for each recording matrix, connected to a twentieth line (SAM) of corresponding multiple gates (PAM 2301);

an eighth bistable memorization element (BH 2309) to indicate that in inter-processing priority has been authorized in the relative, respective recording matrix (CI); and

a classification circuit for the recording matrices, connected to the outputs of the seventh memorization elements (BAM 2304) and to the inputs of the eighth memorization elements (BH 2309) to authorize energization of the specific eighth bistable memorization element (BH 2309) which corresponds to the first matrix, taken in the order of hierarchy between the matrices, and in which the specific seventh element (BAM 2304) contains data in its memory.

22. Apparatus according to claim 21, wherein the matrix classification circuit (FIG. 23) comprises a loop line, having connected thereto as many twenty-fifth AND gates (2305) as matrices are present to arrange in hierarchical order, all said twenty-fifth AND gates (2305) being permanently energized, except that particular one corresponding to the first matrix in the hierarchical arrangement, each of said twenty-fifth AND gates (2305) being additionally connected, over an inverter (I 2307) to the input of a twenty-sixth AND gate (2308), a twenty-first OR gate (2306) being connected to the output of the seventh memorization elements (BAM 2304) and being interposed in the loop line after each of said twenty-fifth AND gates (2305).

23. Apparatus according to claim 21, wherein the inter-data processing priority circuit (FIG. 23) comprises

a control element (COM 2201) connected to a first input line (MEP) connected to the output of the eighth bistable memorization element (BH 2309) and to a second input line (MODH), said second input line (MODH) being connected to the output

of said eighth memorization element (2309) by means of a twenty-seventh AND gate (2312), energized from the output of said seventh bistable memorization element (BAM 2304);

a second loop line (FIG. 22) and as many twenty-seventh AND gates (1404) interconnected in said loop line as possible values of action can be recorded in the matrix, all said twenty-seventh AND gates (1404) being energized by said control element (COM 2201), except that corresponding to the first data processing step to be taken in the hierarchy; and

each said thirteenth interrogation lines (FIG. 22: INT CAA) including a twenty-first AND gate (1402), the input of which being connected to the output of the corresponding twenty-seventh AND gate (1404) over an inverter (I 1406), the fourteenth authorization line (AUT CAA) being connected to said loop in advance of the subsequent twenty-seventh AND gate (1404), by means of a twenty-second OR gate (1405).

24. Apparatus according to claim 23, wherein the twenty-first AND gates (1402) have three inputs, the third input being connected across a twenty-third OR gate (1403) to the output of twentieth AND gates (1401), the inputs of which being connected to the fourteenth authorization lines (AUT CAA).

25. Apparatus according to claim 1, wherein the recording lines (FIG. 11a: SORT ACT 0) of all the recording matrices are connected to the inputs of a twenty-eighth AND gate (PACN), the output of which is connected to one of the inputs of a nineteenth OR gate (2401).

26. Apparatus according to claim 1, wherein the outputs (INF B0) of the first memorization elements (FIG. 8: B0 1108) of the connecting elements (EL) corresponding to a matrix are connected to display elements (FIG. 11a: SAFI) associated with the matrices, the outputs of the display elements (SAFI) being connected to the inputs of the sixteenth AND gates (FIN EXT), the output of which controlling the termination of search by the coordination center (CC).

27. Apparatus for the extraction of information for use with data processing apparatus which includes matrices having bistable elements, and temporary memories;

a coordination center (CC) controlling the bistable matrices and the temporary matrices,

said apparatus analyzing an external system defined by a plurality of parameters, each capable of taking a finite number of values and to undergo, starting from each said values, a finite number of variations, the data processing machine comprising

I. a plurality of basic, functionally non-subdivisible sub-assemblies including

a. as many connection centers (FIG. 3: CL; CLX, CLY . . .) as there are parameters to be memorized, each connection center (CL) comprising as many connection elements (FIG. 8: EL) as there are possible values for the parameter to be considered, each connection element (EL) comprising at least one separate first bistable memorization element (B0 1108);

b. as many bi-dimensional recording centers in matrix form (FIG. 3: CI; CIX, CIY . . .) as there are parameters in the system, each recording center (CI) comprising recording elements (FIG. 9: EI) included in the recording center matrices, each recording element comprising at least one separate second bistable memorization element (B 1201), each state of said second bistable memorization element corresponding to one of the possible variations of one of the values of the parameter of the respective matrix, and a 1203 AND gate controlled from the output from the second bistable memorization elements (B 15 1201);

(c) at least one value-associative matrix (FIG. 3: CAS; CAS XY . . .) comprising as many association elements (FIG. 7: EAS) as the number of possible associations, and having a plurality of third bistable memorization elements (FIG. 7: B 1004, B1 1007, B2 1012), each state of which corresponds to a different parameter, and a 1011 AND gate controlled from one of said third bistable elements; and 25

II. a data extraction and interconnection system comprising

a. a first group of four types of interconnecting lines, interconnecting the connecting elements (FIG. 8: EL), with respect to a predetermined parameter, to the recording elements (FIG. 9: EI) with respect to the same said parameter, said four types of lines including:

1. an INT OACI line (FIGS. 8 and then 9) interconnecting a connecting element (EL) to an input of said 1203 AND gate of a row of recording elements (EI) associated with one of said values; 35

2. AUT OACI lines (FIGS. 9 and then 8) interconnecting the output from a recording element (EI) to the first input of a 1111 AND gate of a corresponding connecting element (EL), the output of which is connected to a 1113 control gate; 45

3. INT EACI lines (FIGS. 8 and then 9) interconnecting the output of a connecting element (EL) representative of and corresponding to a particular value of a parameter, to second inputs of said 1203 AND gates of the recording elements (EI) so that the variation of a value of the parameter corresponding to the columns in which each recording element (EI) is arranged defines the same extreme value for the array of recording elements (EI) connected to the INT EACI line and said extreme value is that of said connecting element (EL); 55

4. AUT EACI lines (FIGS. 9 and then 8) interconnecting the outputs of the recording elements (EI) to a first input of a 1112 control gate of a corresponding connecting element (EL); 65

b. SORT ACT recording lines interconnecting the recording elements (FIG. 9: EI), each of

said SORT ACT recording lines (FIG. 11) corresponding, for the same column of a recording matrix, to the same variation controlling the actual value of the parameter;

c. a second group of three types of interconnecting lines, interconnecting the connecting elements (FIG. 8: EL), each, with respect to a value of a parameter to at least a row of value-associative elements (FIGS. 3 and 7: EAS), of the value-associative matrix (CAS), with respect to the same value of a parameter including:

1. INT CAS lines (FIGS. 8, then 7: INT CAS X, INT CAS Y) interconnecting the outputs of said 1113 AND gate of a connecting element (EL) to at least one of two inputs (INT CAS X, INT CAS Y . . .) of 1006 AND gates (FIG. 7) of a row of associative elements (EAS), the center of association (CAS) formed by a group of said value-associative elements (EAS), being associated with a predetermined value with respect to said parameter, the outputs of said 1006 AND gates being connected to control one of said third bistable elements (1007); and

2. at least two RET B1 lines for each center of association (CAS) controlling and associated with a predetermined value (RET B1X, RET B1Y . . .), each line being associated with at least two rows of value-associative elements (EAS) of at least one center of association (CAS) associated with said predetermined value, for each parameter, each row of elements (FIG. 7: EAS) being connected to an input of the 1106 AND gate of the connecting element (FIG. 8: EL) corresponding to the value of the parameter defined by said row;

3. at least two RET B2 lines for each center of association (CAS) of the same determined value (FIG. 7: RET B2XX, RET B2YY . . .), each line being associated with at least two rows of value-associative elements (EAS) of at least one center of association (CAS) of said predetermined value, for each parameter, each row of elements (FIG. 7: EAS) being connected to an input of a 1101 AND gate of the connecting element (FIG. 8: EL) corresponding to the value of the parameter defined by said row;

d. as many MEM B2 display lines (FIG. 8) of the values for the group of parameters corresponding to the final state of the system to be controlled, as are possible values for each parameter, each said MEM B2 lines being connected to a connecting element (EL) with corresponds to the same value of the same parameter;

e. as many MEM B0 control lines (FIG. 8) of the values for the group of parameters corresponding to the initial state of the system to be controlled as are possible values for each parameter, each said MEM B0 lines being connected to a connecting element (EL) which corresponds to the same value of the same parameter;

- f. the coordination center (CC) executing, step by step, the different phases of analysis and comprising:
1. lines γ connected to at least some of said control gates of the connecting elements (FIG. 8: EL);
  2. start lines (A) connected to all the connecting elements (FIG. 8: EL);
  3. control lines (RAZ B1, RAZ B2, FIN β CAS), connected to the value association elements (EAS); and
  4. AUT SORT ACT control lines (FIG. 11b) connected to control energization by said

15

- SORT ACT recording lines (FIG. 9), of the same column of recording elements (EI) in a recording matrix (CI);
5. INF BO lines (FIG. 8), and a comparator (FIG. 11a: SAFI) connected to sense a predetermined condition and, upon such sensing, interrupting the extraction step; and
  6. a clock means providing timing signals (FIG. 15) to said apparatus until said predetermined condition is sensed and the extraction steps interrupted.

UNITED STATES PATENT OFFICE
CERTIFICATE OF CORRECTION

Patent No. 3,688,278

Dated August 29, 1972

Inventor(s) Jacques Louis SAUVAN, et al

It is certified that error appears in the above-identified patent and that said Letters Patent are hereby corrected as shown below:

In the heading, please add the following Assignment data:

--[73] Assignee: SOCIETE NATIONALE D'ETUDE ET DE CONSTRUCTION DE MOTEURS D'AVIATION,
S.N.E.C.M.A.
Paris, France--.

Signed and sealed this 8th day of May 1973.
